CLAIM

I claim the ornamental design for a wrench with removable jaw inserts, as shown and described.

DESCRIPTION

FIG. 1 is a perspective view of a wrench with removable jaw inserts showing the new design.

FIG. 2 is a front view of the wrench with removable jaw inserts of FIG. 1.

FIG. 3 is a rear view of the wrench with removable jaw inserts of FIG. 1.

FIG. 4 is right side view of the wrench with removable jaw inserts of FIG. 1.

FIG. 5 is a left side view of the wrench with removable jaw inserts of FIG. 1.

FIG. 6 is a top view of the wrench with removable jaw inserts of FIG. 1.

FIG. 7 is a bottom view of the wrench with removable jaw inserts of FIG. 1.

FIG. 8 is an exploded view of the wrench with removable jaw inserts of FIG. 1.

FIG. 9 is a perspective view of a first removable jaw insert of the wrench with removable jaw inserts of FIG. 1.

FIG. 10 is another perspective view of the first removable jaw insert of FIG. 9.

FIG. 11 is a front view of the first removable jaw insert of FIG. 9.

FIG. 12 is a rear view of the first removable jaw insert of FIG. 9.

FIG. 13 is a left side view of the first removable jaw insert of FIG. 9.

(Continued)

FIG. 14 is a right side view of the first removable jaw insert of FIG. 9.

FIG. 15 is a top view of the first removable jaw insert of FIG. 9.

FIG. 16 is a bottom view of the first removable jaw insert of FIG. 9.

FIG. 17 is a sectional view of the first removable jaw insert of FIG. 9 taken along line "17-17" in FIG. 13.

FIG. 18 is a perspective view of a second removable jaw insert of the wrench with removable jaw inserts of FIG. 1. FIG. 19 is another perspective view of the second removable jaw insert of FIG. 18.

FIG. 20 is a front view of the second removable jaw insert of FIG. 18.

FIG. 21 is a rear view of the second removable jaw insert of FIG. 18.

FIG. 22 is a left side view of the second removable jaw insert of FIG. 18.

FIG. 23 is a right side view of the second removable jaw insert of FIG. 18.

FIG. 24 is a top view of the second removable jaw insert of FIG. 18.

FIG. 25 is a bottom view of the second removable jaw insert of FIG. 18; and,

FIG. 26 is a sectional view of the second removable jaw insert of FIG. 18 taken along line "26-26" in FIG. 23.

The broken line showing of the wrench with removable jaw inserts is for the purpose of illustrating portions of the article and forms no part of the claimed design.

1 Claim, 15 Drawing Sheets
